HOUSING FOR AN AQUARIUM HEATER

Seymour Bergen, 14 Lewis Lane, Port Washington, N.Y.

Filed Nov. 29, 1960, Ser. No. 63,013

Term of patent 14 years

(Cl. D81—2)

FIG. 1

FIG. 2

FIG. 3

FIG. 4

FIG. 5

FIG. 6

FIG. 7

FIGURE 1 is a front elevational view of a housing for an aquarium heater, showing my new design;

FIGURE 2 is a side elevational view thereof;

FIGURE 3 is a rear elevational view thereof;

FIGURE 4 is a top view thereof;

FIGURE 5 is a bottom view thereof;

FIGURE 6 is a side elevational view thereof with the cover removed; and

FIGURE 7 is a top plan view thereof with the cover removed.

I claim:

The ornamental design for a housing for an aquarium heater, substantially as shown.
